UNITED STATES PATENT OFFICE.

CHARLES O. WYMAN, OF ANOKA, MINNESOTA.

INTERNAL-COMBUSTION ENGINE.

1,370,939.

Specification of Letters Patent.

Patented Mar. 8, 1921.

Application filed May 4, 1916. Serial No. 95,355.

To all whom it may concern:

Be it known that I, CHARLES O. WYMAN, a citizen of the United States, resident of Anoka, county of Anoka, State of Minnesota, have invented certain new and useful Improvements in Internal-Combustion Engines, of which the following is a specification.

My invention relates to engines using gasoline or other suitable explosive as a fuel and the object of my invention is to provide a construction by means of which an explosion will occur with each stroke of the piston, dispensing with the scavenging stroke usually incidental to engines of the four-cycle type.

A further object is to dispense with the usual cam shafts and operate the valves from the crank shafts, provision being made for an explosion with every revolution of the shaft.

A further object is to provide an engine of comparatively inexpensive construction and of high efficiency.

Other objects of the invention will appear from the following detailed description.

The invention consists generally in various constructions and combinations, all as hereinafter described and particularly pointed out in the claim.

In the accompanying drawings forming part of this specification,

Figure 1 is a vertical sectional view through a cylinder of an internal combustion engine embodying my invention, showing the piston at the beginning of the explosion stroke,

Fig. 2 is a sectional view taken on a line at right angles substantially to the section line of Fig. 1, showing the auxiliary piston at the beginning of the stroke for discharging the burned gases,

Fig. 3 is a view corresponding to Fig. 2, showing the piston at the beginning of the compression stroke,

Fig. 4 is a vertical sectional view of a modified construction,

Fig. 5 is a similar view of another modification,

Fig. 6 illustrates still another modification.

In the drawing, 2 represents a crank case and 3 the cylinder of an internal combustion engine. Only one cylinder is shown, but it will be understood that any desired number may be used, the structure of all of them

being substantially the same. 4 represents a double crank shaft and 5 the main piston of the engine cylinder having a wrist pin 6 and a connecting rod 7 between the wrist pin and the crank shaft. 8 is an auxiliary piston mounted above the piston 5 and provided with a sleeve 9 which fits within a hole 10 in the wrist pin, the hub 11 of the connecting rod 7 having openings 12 of sufficient width therein to permit the rocking of the hub of the wrist pin in following the stroke of the connecting rod without affecting the sleeve 9. A rod 13 is mounted to telescope with the sleeve 9 and has a rocking connection at 14 with the auxiliary connecting rod 15 which has one end mounted on the crank shaft 4. The auxiliary piston is provided with a valve 16 and the cylinder has a gas intake valve 17 provided with a push rod 18 and also has an exhaust valve 19 connected to one end of a rocking arm 20, the other end of which is pivotally connected to a push rod 21. The rod 18 is positioned to be actuated by a cam 22 on a shaft 23 that is driven from a gear 24 on the crank shaft and the rod 21 is actuated by a cam 22^a on the shaft 23^a that is also geared to the crank shaft. The movement of these valves is so timed that at the end of the explosion stroke the exhaust valve and the gas intake valve will be opened, as shown in Fig. 2, one crank of the shaft being a quarter of a revolution ahead of the other crank, so that when the auxiliary rod 15 begins its upward movement it will push the auxiliary piston from the position shown in Fig. 2 to that illustrated in Fig. 3. During this initial upward movement of the auxiliary piston the burned gases still in the combustion chamber will be forced out through the exhaust valve and a fresh charge will be sucked in to the space between the main piston and the auxiliary piston, as indicated in Fig. 3. When this charge has entered, the main piston will begin its upward movement, its crank having passed the center during the upward stroke of the auxiliary piston. When the main piston begins its upward movement, the auxiliary one will nearly have completed its stroke and its movement will be less, and consequently the upward travel of the main piston will open the valve 16 and force the fresh charge of gas through this valve into the space between the head of the cylinder and the auxiliary piston, the exhaust valve

in the meantime having closed to prevent the escape of the charge.

During the movement of the pistons the rod 13 will slide in the sleeve 9, adapting 5 itself to the different positions of the crank shaft and on the beginning of the upstroke of the auxiliary piston the sleeve and rod will be in the position shown in Fig. 2, where the initial movement of the rod 15 will immediately 10 actuate the auxiliary piston to expel the burned gases from the combustion chamber.

In Fig. 4 I have shown a modified construction, which consists in mounting a cylinder 25 provided with air cocks 26 and 27 15 and a plunger 28 connected by a rod 29 with an auxiliary piston. The downward movement of the auxiliary piston will draw the plunger 28 down with it, putting the air in 20 the lower end of the cylinder 25 under compression so that when the valve 19 is opened to permit the discharge of the burned gases at the end of the explosion stroke the auxiliary piston will be raised or drawn away 25 from the main piston to hasten the discharge of the gases through the exhaust port.

In Fig. 5 another modification is shown, which consists in mounting a rod 30 on the auxiliary piston to extend up through the 30 head of the cylinder, said rod being pivotally connected to a walking beam 31 which is loosely mounted at 32 upon a rod 33 that is slidable in a bracket 34 that is connected by a link 35 with the beam 31. The rod 33 35 has a hollow end 36 in which a pin 37 is slidable and connected with a crank 38 by a rod 39. The pin 37 is positioned to contact with the rod 33 at the end of the hollow portion thereof to push it upwardly and raise the 40 auxiliary piston to expel the burned gases when the exhaust valve is opened. This auxiliary piston is forced down with the main piston during the explosion stroke.

In Fig. 6 another modification is shown, in 45 which a walking beam 40 is pivoted on a link 41 that is mounted on the engine cylinder, one end of the beam being connected to the rod 30 on the auxiliary piston and the other end of the beam having a long helical 50 spring 42 connecting it with the crank case, said spring normally tending to raise the auxiliary piston away from the main piston but allowing these two pistons to follow one another on the explosion stroke. In other 55 respects, the mechanism shown in Fig. 6 is

substantially the same as described with reference to the preceding figures.

In Figs. 1, 2 and 3 the auxiliary piston is shown provided with a boss or projection 43 on the underside thereof to enter a recess 44 60 in the top of the main piston, these two elements forming a check or buffer in the nature of a dash-pot to prevent shock or jar of the pistons as they come together during the explosion stroke. 65

In Fig. 6 a similar mechanism is employed, except that the position of the parts is reversed, the boss 43^a being on the top of the piston and the recess 44^a in the head of the cylinder. 70

With this apparatus the burned gases will be positively expelled and the usual scavenging stroke of the engine eliminated, a fresh charge of gas being drawn into the cylinder on the upstroke of the main piston, following the explosion stroke, which is usually required for expelling the waste gases after combustion has taken place. 75

As there is an explosion with every revolution, it is evident that the cams for operating the valves may be mounted on the crank shaft, and thereby eliminate, if desired, the use of the cam shafts. In this application, however, I have shown the cam shafts geared to the crank shaft to operate 85 at the same speed, with suitable mechanism between the shafts and the valves. 80

In various ways the details of construction herein shown and described may be modified and still be within the scope of my 90 invention.

I claim as my invention:

An internal combustion engine comprising a cylinder and a shaft having double cranks thereon, a piston mounted in said cylinder 95 and having a connecting rod journaled on one of said cranks, an auxiliary piston mounted at one end of said main piston, a connecting rod mounted on the other crank of said shaft and having a sliding connection with said auxiliary piston, movement of said auxiliary piston connecting rod operating to advance said auxiliary piston with respect to said main piston at a predetermined point in the stroke of said main 105 piston. 100

In witness whereof, I have hereunto set my hand this 25 day of April 1916.

CHARLES O. WYMAN.
